UNITED STATES PATENT OFFICE

2,625,422

TOOL FOR HANDLING PACKAGES OF YARN

Samuel B. Roberts, Greenwich, Conn., and Bradford C. Gibbs, Teaneck, N. J., assignors to Celanese Corporation of America, New York, N. Y., a corporation of Delaware

Application May 9, 1950, Serial No. 160,966

5 Claims. (Cl. 294—15)

1

The invention relates to tools and relates more particularly to a tool for handling packages of yarn.

In the textile industry, it is common practice to form packages of yarn by winding yarn onto a tubular support. Great difficulty has been experienced in the handling of the yarn packages during production, inspection, transfer, wrapping, packing and other operations wherein manual contact with the packages of yarn is necessary. Since the packages of yarn may weigh up to four or more pounds and since they are normally not provided with means for handling the same whereby contact with the yarn may be avoided, the danger of soiling and damaging the yarn and of disarranging the windings on the yarn packages is ever present even with the most careful handling of the yarn packages by skilled operatives.

It is an important object of this invention to provide a tool for handling packages of yarn which will overcome the difficulties previously experienced in handling said packages of yarn and which will be especially simple in construction and efficient in use.

A further object of this invention is the provision of a tool for handling packages of yarn which will engage said packages without contacting the yarn so as to avoid damage to the yarn or to the uniformity of the winding on said packages.

Other objects of this invention will be apparent from the following detailed description and claims.

The present invention is particularly concerned with handling cones of yarn, each of which comprises a tubular support of generally conical shape having yarn windings thereon, and having at one end thereof an internal rim forming a circular opening communicating with the interior of the tubular support. For handling these cones of yarn to prevent contact with the yarn windings thereof, we have provided a tool comprising a finger adapted to enter into the tubular support, which finger is operatively connected to a handle of convenient size and shape. The finger is provided with means, such as a notch, for engaging the rim of the tubular support when the finger is inserted in the interior of the tubular support, and with the area adapted to contact the interior of the tubular support at a point spaced from the rim and diametrically opposed to the point at which the rim is engaged. Advantageously, the handle lies in the plane of the finger and is inclined at an angle in the same

2

general direction as that in which the notch opens so that when the tool is engaged with a package of yarn, the handle will be inclined with respect to the axis of the tubular support. The inclination of the handle serves to improve the ease with which the tool may be handled in that a person using said tool need bend his wrist to only a limited extent to insert or remove the finger from engagement with the tubular support when the cone is positioned on a horizontal surface with the tubular support disposed vertically. It also serves to align the tool in the hands of a user for proper engagement with the cone.

Preferred embodiments of this invention are shown in the accompanying drawing wherein

Fig. 1 is a perspective view of the tool,

Fig. 2 is a side elevational view, partly in cross-section, showing the engagement of the tool with a cone of yarn during the lifting thereof, and

Fig. 3 is a perspective view of a gang tool for simultaneously handling a plurality of cones of yarn.

Referring now to the drawing, the reference numeral 11 (see Figure 2) designates generally a cone of yarn, comprising a tubular support 12 of conical shape having thereon yarn windings 13. At its upper or narrower end, the tubular support 12 is provided with an internal rim 14 forming an opening 15 which communicates with the interior of the tubular support.

For handling the cones 11, there is provided a tool, indicated generally by reference numeral 16. The tool 16 comprises a handle 17, having a circular boss 18 at one end thereof. Projecting from the under surface of the boss 18 is a finger 19 that is of such size and shape as to pass readily through the opening 15. In one surface of the finger 19, there is a notch 21 having a surface 22 that is normal to the plane of the undersurface of the boss 18 and a shoulder 23 that is normal to the plane of surface 22. The finger 19 is curved in a direction away from that in which the notch 21 opens and terminates in a surface 24 for engaging the interior of the tubular support 12.

During use, the finger 19 of the tool 16 is inserted through the opening 15 and into the interior of the tubular support 12. Upon raising the cone 11, the notch 21 will engage the rim 14 to prevent the cone 11 from slipping off the tool 16 and the surface 24 will abut the inner surface of the tubular support 12 at a point spaced from said rim and diametrically opposed to that at which the notch 21 engages the rim 14. As shown in the drawing, the surface 24 is inclined so that

it will contact the inner surface of the tubular support 12 over an extended area when the cone 11 is raised, to avoid the application of concentrated forces to said support.

The handle 17 lies in the plane of the finger 19 and is inclined at an angle of from about 30 to 60 degrees in the same general direction as that in which the notch 21 opens. Because of the inclination of the handle 17, a person handling the tool 16 need bend his wrist to only a limited extent to insert or remove the finger 19 from the opening 15 when the cone 11 is positioned on a horizontal surface with the tubular support 12 disposed vertically, making for easier use of the tool. In addition, the inclination of the handle 17 tends to align the tool 16 automatically in the hands of a user with the notch 21 and the surface 24 positioned properly to engage the tubular support 12, at the rim 14 and the interior surface, respectively.

Fig. 3 shows a gang tool, indicated generally by reference numeral 25, for simultaneously handling six cones 11. The tool 25 comprises a rectangular bar 26, to one surface of which is fastened a pair of handles 27 and from the other surface of which project six fingers 28 identical in construction with the finger 19. While the tool 25 has been shown as having six fingers 28 for handling six cones of yarn, it may have a smaller or larger number of fingers 28 for handling any desired number of cones of yarn.

It is to be understood that the foregoing detailed description is given merely by way of illustration and that many variations may be made therein without departing from the spirit of our invention.

Having described our invention, what we desire to secure by Letters Patent is:

1. In a tool for handling a package of yarn comprising a tubular support having an opening communicating with the interior thereof and having a yarn winding thereon, a handle, and a finger operatively connected to said handle of such size and shape as to pass readily through said opening, said finger including means for engaging one end of said tubular support, and a flat surface for contacting the interior of the tubular support at a point spaced from the end of the tubular support and diametrically opposed to the point at which the end of the tubular support is engaged.

2. In a tool for handling a package of yarn comprising a tubular support provided at one end thereof with an internal rim and an opening communicating with the interior thereof and having a yarn winding thereon, a handle, and a finger operatively connected to said handle of such size and shape as to pass readily through said opening, said finger including a shoulder for engaging said rim, and a flat surface spaced from said shoulder for contacting the interior of the tubular support at a point spaced from the rim and diametrically opposed to the point at which the rim is engaged.

3. In a tool for handling a package of yarn comprising a tubular support provided at one end

thereof with an internal rim and an opening communicating with the interior thereof and having a yarn winding thereon, a handle, and a finger operatively connected to said handle of such size and shape as to pass readily through said opening, said finger including a notch for engaging said rim, and a flat surface spaced from said notch for contacting the interior of the tubular support at a point spaced from the rim and diametrically opposed to the point at which the rim is engaged.

4. In a tool for handling a package of yarn comprising a tubular support provided at one end thereof with an internal rim and an opening communicating with the interior thereof and having a yarn winding thereon, a handle, and a finger operatively connected to said handle of such size and shape as to pass readily through said opening, said finger including means for engaging said rim, and a flat surface for contacting the interior of the tubular support at a point spaced from the rim and diametrically opposed to the point at which the rim is engaged.

5. In a tool for handling a cone of yarn comprising a tubular support of conical shape provided at one end thereof with an internal rim and an opening communicating with the interior thereof and having a yarn winding thereon, a handle, and a finger projecting from said handle of such size and shape as to pass readily through said opening, said finger including a notch for engaging said rim, and a flat surface spaced from said notch for contacting the interior of the tubular support over an extended area at a point spaced from the rim and diametrically opposed to the point at which the rim is engaged, said handle lying in the plane of the finger and extending from the finger at an angle of from about 30 to 60 degrees in the same general direction as that in which the notch opens so that the handle will be inclined with respect to the tubular support when the tool is engaged with a package of yarn.
